UNITED STATES PATENT OFFICE.

WILLIAM JOSEPH PAUL, OF PITTSBURG, PENNSYLVANIA.

DESIGN FOR A VENDING-MACHINE CASING.

No. 38,902.

Specification for Design.

Patented Nov. 26, 1907.

Application filed August 31, 1907. Serial No. 390,958. Term of patent 3½ years.

To all whom it may concern:

Be it known that I, WILLIAM JOSEPH PAUL, a citizen of the United States, residing at Pittsburg, in the county of Allegheny and State of Pennsylvania, have invented a new, original, and ornamental Design for Vending-Machine Casings, of which the following is a specification, reference being had to the accompanying drawing, forming part thereof.

The figure is a perspective view of a vending machine casing, showing my new design.

I claim:

The ornamental design for a vending machine casing, as shown.

WILLIAM JOSEPH PAUL.
